UNITED STATES PATENT OFFICE.

JAMES PORTEOUS, OF FRESNO, CALIFORNIA.

DIRT-SCRAPER.

SPECIFICATION forming part of Letters Patent No. 289,134, dated November 27, 1883.

Application filed June 22, 1883. (No model.)

To all whom it may concern:

Be it known that I, JAMES PORTEOUS, of Fresno, county of Fresno, and State of California, have invented an Improvement in Dirt-Scrapers; and I hereby declare the following to be a full, clear, and exact description thereof.

My invention relates to the class of dirt-scrapers for leveling land, and to certain new and useful improvements therein.

These improvements consist in the means for regulating the dump of the bowl, hereinafter fully described. The object in this is to cause the bowl to discharge its load more or less quickly by regulating the distance of its bit from the ground when in a dumped position. In case of a decided depression in the ground, it becomes necessary to discharge the load at once, and this is accomplished by so regulating the dump of the bowl that its bit shall be high enough from the ground to let the dirt escape. In case but a thin layer need be spread, the bit is raised but little, and it acts as a scraper, spreading the slowly-discharging earth over a greater surface. This result—namely, the limiting of the dump of the bowl—has been heretofore accomplished by means of a bar set transversely over the top between the ends of the bowl, said bar coming in contact with the draft-rods, as shown in Letters Patent No. 275,075, issued to me April 3, 1883; but to this position of the bar or stop there may be some objection, which I overcome by my present improvements.

Referring to the accompanying drawings, Figure 1, Sheet 1, is a perspective view of my scraper shown in position to take a load. Fig. 2 is a side elevation of the scraper shown in a dumped position. Fig. 3, Sheet 2, shows a modification of the means for adjusting the stop-bar G. Figs. 4 and 5 show other modifications of the same.

A is the bowl, having bit a.

B are the ends of the bowl, and C are its wheels, mounted in the ends.

D is the handle, extending rearwardly from the bowl.

E are the draft-rods, pivoted to the inner surfaces of the ends of the bowl, and extending and converging forward to the tongue or pole F, to which they are secured. The rear end of this pole extends rearwardly behind the point at which the draft-rods are secured,

and is braced by a cross-bar, f. When the load is in the bowl, the driver throws up the handle D, turning the bowl on its wheels, 55 the pivoted draft-rods permitting it, until the upper edge of the bowl comes in contact with the rearwardly-extending end of the pole F, whereby its dump is limited; but while this limit is effective, I find it best to provide certain positive stops or bumpers, as follows: The first should be attached to the top center of the bowl, and be adapted to come in contact with the pole, or with a stop or bumper on said pole, and the second should 60 be the reverse of the first.

G is a bar having a curved forward end, which passes through a socket, a', on the top center of the bowl, and extends forward over the top edge of said bowl. Its rear end passes 70 back beside handle D, and is guided by a staple, d, in said handle. When the bowl is dumped, the forward end of bar G comes in contact with the rear end of pole F and limits the dump of said bowl. The bar G serves 75 a further purpose by reason of its curvature at its rear end—namely, it affords a better opportunity, because it is closer, for the driver to lay hold of and draw the handle D back within reach. Upon the rear end of the pole 80 is secured a stop or bumper, H, with which the top edge of the bowl may come in contact when dumped, or which the stop-bar G may strike, Fig. 2; but though these devices limit the dump of the bowl, it is essential that the 85 limit should be an adjustable one, to provide for discharging the load more or less quickly in a heap or spread over, as heretofore explained. To do this the stops or bumpers must be rendered adjustable forward or back, 90 so that they shall come in contact at shorter or longer distances in the dump of the bowl, to barely raise its bit from the ground or elevate it considerably. The bar G has a series of holes, g, on its forward end, the socket a' is 95 perforated, and a pin or bolt, g', passes through said socket and bar. In this manner the bar may be set forward or back.

The stop or bumper H on the pole is made in the shape of an inclined plane, and has a 100 forwardly-extended shank, h, slotted as shown, and having a set-screw, h', passing through it into the pole. By loosening this screw, the stop may be pushed farther back, to cause the

bowl to strike it sooner, or moved forward, to cause it to strike it later, and it may be set in any position.

I do not confine myself to the particular means I have shown for adjusting these stops or bumpers, and I may modify these means as I show in Fig. 3. In this two parallel spaced braces, d' , extend between the handle D and the rear top center of the bowl. These are 10 perforated, as shown. The stop-bar G lies in and slides between these braces, and is also perforated. The bolt g' passes through these perforations. A small handle, g'' , is made upon the rear of the stop-bar, to enable the 15 driver to move it forward or back.

In Fig. 4 I show another modification. In this the handle D is straight and is braced from below. The stop-bar G lies alongside of the handle and slides in the guide-staples d . 20 On the other side of the handle is fulcrumed, at j , a lever, I , having on its forward end a pin, i , which passes through a hole in the handle, and is adapted to enter any of the perforations g in the stop-bar G . A spring, J , 25 holds and returns said lever to position.

Another modification is shown in Fig. 5. The forward end of stop-bar G is ratcheted, and engages with a pin, a' , in socket a' , being held to its engagement by a spring, s , in a boxing on the socket. The central position of 30 these stops renders them very convenient and makes a compact device, avoiding clumsiness and unworkman-like construction. The limits of adjustment are very wide, so that the scraper 35 can be rendered serviceable for all kinds of work.

It is obvious that by putting the cross-bar f of the pole farther back, and by elevating it or increasing its thickness, the bowl or its bar 40 may be made to strike it or a bumper upon it; but this is the equivalent of devices I have shown, and I have not therefore deemed it necessary to show it. Likewise, the bar G might be made forked, and strike the cross-bar on each side; or bumpers might be placed 45 in position on each side.

I hereby reserve to myself the right to make 50 separate applications for Letters Patent for the modified forms of construction shown but not claimed in this application.

Having thus described my invention, what I claim as new, and desire to secure by Letters Patent, is—

1. In a dirt-scraper, the turning bowl A , a 55 stop or bumper thereon, and means, substantially as described, for rendering said stop ad-

justable forward or backward upon the bowl, in combination with the pole F , with which said adjustable stop is adapted to engage to limit the dump of the bowl.

2. In a dirt-scraper, the turning bowl A and a stop or bumper thereon, in combination with the pole F , a stop or bumper thereon, and a means for adjusting the latter stop or bumper forward or back, substantially as and for the 65 purpose herein described.

3. In a dirt-scraper, the turning bowl A , the stop or bumper thereon, and a means for rendering said stop adjustable forward or back, in combination with the pole F , a stop or bumper thereon, and a means for adjusting said stop or bumper forward or back, substantially as and for the purpose herein described.

4. In a dirt-scraper, the turning bowl A , having handle D and socket a' , and the stop-bar G , guided past the handle, passing through the socket and extending in front of the bowl, in combination with the pole F , with the rear end of which the stop-bar G is adapted to come in contact, to limit the dump of the scraper, 75 substantially as herein described.

5. In a dirt-scraper, the turning bowl A , having handle D , the stop-bar G , and the means for rendering it adjustable forward or back, consisting of the perforated socket a' on 85 the bowl, the series of perforations g in the end of the stop-bar, and the pin or bolt g' , in combination with the pole F , substantially as and for the purpose herein described.

6. In a dirt-scraper, the turning bowl A , in 90 combination with the pole F , the inclined stop H , and means for rendering it adjustable forward or back to variously limit the dump of the bowl, substantially as herein described.

7. In a dirt-scraper, the turning bowl A , in 95 combination with the pole F , the inclined stop H , and the means for adjusting it, consisting of the slotted shank h of the stop, and the set-screw h' , substantially as and for the purpose herein described.

8. In a dirt-scraper, the turning bowl A , having handle D , and the adjustable stop-bar G , in combination with the pole F and the adjustable inclined stop H thereon, substantially as and for the purpose herein described.

In witness whereof I have hereunto set my hand.

JAMES PORTEOUS.
